UNITED STATES PATENT OFFICE.

EDWARD ANDERSON, OF DENVER, COLORADO, ASSIGNOR OF ONE-TENTH TO J. HARRY MOORMAN, OF DENVER, COLORADO.

LOCK.

Application filed March 3, 1921. Serial No. 449,505.

To all whom it may concern:

Be it known that I, EDWARD ANDERSON, a citizen of the United States, residing at Denver, in the county of Denver and the State of Colorado, have invented a new and useful Lock, of which the following is a specification.

The present invention is directed to improvements in locks, and more particularly to one of the pad-lock type.

The primary object of the invention is to provide a device of this character constructed in such manner that it will be practically impossible to pick the same.

A further object of the invention is to provide a lock so constructed that the shackle thereof will be firmly locked, but readily released upon inserting a key and exerting pressure thereon in a direction longitudinal of the lock body.

Still another object of the invention is to produce a lock constructed in such manner that in the manufacture thereof different combinations may be produced.

In the accompanying drawing:—

Figure 1 is a vertical central sectional view.

Figure 2 is a sectional view on line 2—2 of Fig. 1.

Figure 3 is a sectional view on line 3—3 of Fig. 1.

Figure 4 is a sectional view on line 4—4 of Fig. 1.

Figure 5 is a detail view of the key.

The lock comprises a body 1 having formed therein sockets 2 and 3, and in the former is slidably and pivotally engaged the arm 4 of the shackle 5, said arm having shoulders 6 formed therein. A transverse pin 7 is carried by the body and co-operates with the shoulders 6 to limit the sliding movement of the shackle arm. The arm 8 of the shackle is adapted to slidably engage the socket 3 and has formed therein a notch 9, there being formed in the arm 4 a similar notch 10.

A rectangular recess 11 is formed in the body 1, and located therein are side wall plates 12, which support cross pins 13, two of which are employed, the purpose of which will appear later.

Formed centrally in the body 1 is an elongated chamber 14, the upper end of which is closed by a plate 15 in which is formed a perforation 16 and a plurality of radially

arranged holes 17, preferably four in number. Slidably mounted in the perforation 17 is a rod 18, said rod having secured thereto in any suitable manner resilient prongs 19, corresponding in number to the openings 17. The rod is further provided with a transverse stop pin 20, the purpose of which will later appear.

The upper end of the rod 18 extends into the recess 11, and has connected thereto a yoke 21, there being a coil spring 22 which has its lower end resting on the yoke while the upper end thereof engages the top 23 of the body 1. Pivots connected to the pins 13 are bell crank levers 24, the inner arms 25 being pivotally connected to the yoke 21 by links 26, while the arms 27 thereof are adapted to engage, respectively, the notches 9 and 10 to hold the shackle 5 in its locked position, and at which time the spring 28 located in the socket 2 will be compressed.

Suitably secured in the chamber 14 is a guide 29, and in which the key 30 slides. The key has a right-angle lip 31 in which is formed an opening 32 so fashioned as to slidably engage the rod 18 and flex the prongs a distance to aline the free ends thereof with the holes 17, the movement of the key being limited in one direction by the engagement of the lip 31 with the pin 20. The lower end of the guide is alined with the key-hole 33.

As shown in full lines in Fig. 1, the shackle is in its locked position. To unlock the shackle the key 30 is directed into the body by the guide 29, the rod 18 being engaged in the opening 32, whereupon continued pressure upon the key will contact the prongs until the lip 31 has engaged the stop pin 20. In this manner the prongs will be brought into direct alinement with the holes 17 in the plate 15 so that further pressure on the key will slide the rod 18 upwardly, thereby rocking the bell cranks 24 to cause the arms 27 thereof to disengage the notches 9 and 10, whereupon the shackle 5 will move upwardly under the action of the spring 28, and at which time the bell cranks 24 and shackle 5 will assume the positions as shown in dotted lines in Fig. 1 of the drawing. Thus the shackle can be swung to its open position, and at which time the arm 4 thereof serves as a pivot. It will be of course understood that the spring 22 will be compressed, and as the key is removed

this spring will positively force the rod downwardly, thereby removing the prongs from engagement with the holes 17.

Upon changing the relative arrangement 5 of the holes 17 and prongs 19 it will be obvious that many combinations may be obtained.

Having thus described the different parts 10 and workings of my invention, that which is new and desired to be secured by Letters Patent:

I claim:

1. A lock comprising a body, a shackle yieldably engaged with the body, a plate 15 connected with the body and having a plurality of holes therein, a bar slidably mounted in the body, a plurality of resilient prongs carried by the bar and normally out of alignment with said holes, bell cranks associated 20 with the body for engaging the shackle to hold the same in its locked position, and a key adapted to engage the prongs to align the same with the holes and force the ends thereof through the holes to rock the bell 25 cranks, as and for the purpose set forth.

2. A lock comprising a body, a shackle yieldably engaged therewith, a plate located in the body and having a plurality of holes formed therein, a bar slidably mounted in 30 the body and having one end extended through the plate, a plurality of resilient

prongs carried by the bar and normally out of alignment with said holes, a yoke carried by the extended end of the bar, bell cranks pivotally connected with the yoke and body and engaged with the shackle to normally hold the same locked, and a key adapted to engage the bar and prongs to flex the latter to align the same with said holes when said key is forced into the body, as and for the 40 purpose set forth.

3. A lock of the class described comprising 45 a body, a shackle pivotally connected to the body, bell cranks pivotally mounted in the body for engaging the shackle to hold the same locked, a bar slidably mounted in the body and having a plurality of resilient prongs fixed at one end thereto, a stop pin carried by the bar, a plate located in the body and having holes therein, and a key 50 adapted to enter the body and engage the stop pin and flex the prongs to cause the same to align with said holes, the movement of the bar in one direction compelling the bell cranks to rock and release the shackle, 55 as and for the purpose set forth.

In testimony whereof I hereunto affix my signature in presence of two witnesses.

EDWARD ANDERSON.

Witnesses:
